UNITED STATES PATENT OFFICE

MARCEL GACHASSIN-LAFITE, OF BRUSSELS, BELGIUM

VISIBLE SHOT CONCENTRATING PROJECTILE FOR SPORTING GUNS

Application filed May 8, 1930, Serial No. 450,616, and in Belgium April 1, 1930.

This invention relates to improvements in projectiles and refers particularly to projectiles containing a charge of lead shot or similar material which is discharged from the case during the flight of the projectile.

The primary object of the present invention is to provide a projectile by means of which the path thereof can readily be followed by the person firing the projectile, while a further object of the present invention is to provide a projectile adapted for lethal purposes, whereby the effective range of the shot is increased by ensuring a more dense distribution of the shot charge at a given distance from the gun in comparison with the distribution of shot produced by firing a cartridge containing shot.

In accordance with the present invention, there is provided, to contain the charge of shot, a case having a restricted aperture at its forward end for the passage of shot away from the case in combination with a forcibly expanded retarding device associated with and larger than the base of said case. By suitably proportioning the area of the retarding device at the rear, the size of the grains of shot and the size of the aperture at the forward end of the case, the projectile may be adapted primarily either for tracing purposes in which case the retarding device is of such a nature as to be easily visible throughout their flight or alternatively as a lethal projectile in which case of course, the retarding device may be less visible throughout the flight.

These advantages and some others will be explained in the theoretical statement following.

It is recognized that in the firing of a shot cartridge of the usual type, there is produced a sudden blow on the wad which overcomes the inertia of the shot charge and projects it first out of the tube of the cartridge and then out of the barrel.

It is also recognized that the charge of shot

takes a spherical form on leaving the barrel and spreads very rapidly after about 35 meters covering a space of more than a square metre. The individual shot which are furthest from the direct line of fire, diverge progressively during the flight, with the result that everything which is aimed at and which is not exactly in the center of the aim, is likely not to be hit by a sufficient number of shot and in the case of animals or birds, either missed or uselessly maimed. This has been remedied to some extent by the choke guns which effect a lengthening of the charge of shot in flight and prevent undue spreading, thus extending the useful range of the shot, but this method increases still more the inconveniences of deformation of the shot and of leading of the barrel. It is recognized, however, that a good choke ensures an advantage in range of about 10 metres over the same shot fired by a smooth gun.

With the projectile according to the present invention, it is possible to calculate the various ballistic and mechanical elements, so that the spreading of the shot only commences at a definite distance, for example, 15 or 20 metres, or even more, from the gun, which will thus ensure that a given grouping of the shot is obtained at a distance of 15 or 20 metres beyond that which would be obtained with an ordinary cartridge. For example, if a parallel bore gun, which an ordinary cartridge fires 245 No. 3 shot into a circle of 0.75 metres in diameter at a distance of 35 metres, the same spreading effect will be attained at 50 or 55 metres according to the construction, with the projectile according to the present invention. Furthermore, due to the reduction of friction in the barrel it is possible to obtain this result by using a smaller charge of powder, with the certainty that none of the shot will fall short.

Further, it is known that it is impossible with an ordinary cartridge, to tell where the shot has carried with respect to the moving

target. With the projectile according to one embodiment of the present invention, it is possible, owing to the visibility of the retarding device, to follow the flight for a distance which can be predetermined by calculation, or even during the whole of this flight.

The present invention is based on the fact that the projectile proper consists of a hollow cylindrical case of elastic material, such as rubber, having an integral hemispherical or pointed head provided with a comparatively reduced opening at its top and attached at its base to a large, forcibly expanded retarding device. The hollow projectile is filled with sporting shot of suitable sizes.

The sudden blow which is produced at the moment of discharge, forces out the projectile and in overcoming the inertia of the shot contained therein, the case is initially pressed against the shot. In consequence of this inertia, during the short moment which follows the discharge, the shots have a tendency to bear against the bottom of the projectile. During all the passage through the barrel, the projecting edges around the rubber envelope are all that rub against the hard metal of the barrel and consequently the lead shot has no occasion to be deformed and they all have the same speed as the hollow envelope. But after leaving the barrel, the retarding device opens and tends to slow down the speed of the projectile; nevertheless this retarding action only operates on the light envelope, and the heavier charge of shot maintaining its independent motion moves towards the exit orifice. But here takes place a very characteristic phenomenon: the mass of the shot preserving a greater speed than that of the envelope, but owing to the smallness of the orifice, there is produced at first a confusion or congestion which prevents their exit (similar to that which is produced for example in the case of a panic in a public hall when all the spectators start at one time towards the only exit); those which are at the edge prevent the exit of the others and are themselves prevented from leaving by the pressure which is produced towards the centre of the opening. It is only at the moment when a kind of order is established, that the opening can be passed through. At this moment, the shots then pass out of the projectile case, which latter continues at a retarded speed. This exit is more or less rapid and more or less early, according to the angle of curve of the head of the projectile, the diameter of the exit orifice and the size of the shot. It is evident that the more the angle of curve approaches a right angle, the more the exit of the shot will be retarded, while if the angle is more obtuse, that is to say, its shape is more pointed, their exit will be facilitated. Evidently this exit will be influenced also by the thickness or the rigidity of the material of the head of the case, by the diameter

of the centre hole, by the size of the shot, and by the greater or lesser retarding effect on the case. With the cartridges called tracing cartridges, intended as we have stated for the correction of the aim, it is necessary that the shot only leave the envelope at a point as far away as possible from the mouth of the barrel, and furthermore, when the projectile is intended for practice or for correction, it is advisable that the shot should be harmless; in this case, a projectile is used with a head of only slight sphericity, with fairly thick and stiff walls, having comparatively small exit orifice and with a charge of very fine shot, preferably of so-called lead dust; under these conditions, it is possible so to arrange the projectile that the shot charge only escapes after the projectile has covered a distance of some 50 metres, thus permitting the person firing to observe the trajectory that would have been followed by the charge of invisible shot aimed at the same point, the speed of this tracing projectile being calculated to correspond to the mean speed of the shot from a sporting gun.

On the contrary, for lethal projectiles, the angle of the head of the case will be more obtuse, the shape of the head being more pointed, the thickness and rigidity of the material of such head being correspondingly less and the exit hole correspondingly larger because the shot are larger and/or have to leave their envelope earlier. In general, for these cartridges the commencement of the evacuation of the killing projectile will vary between 10 and 20 metres from the exit of the barrel, thus ensuring a greater useful range of the weapon by 10 or 20 metres.

It is evident that by properly calculating the charge of powder, the force of the braking, the conicity of the head of the case, the nature of the material used, the size of the exit opening and the size of the shot which it contains, projectiles suitable for all circumstances may be made as desired, for example, projectiles suitable for simply tracing over the whole of the flight, or for tracing over a definite range, or again for tracing over a very long flight, or still further for lethal purposes by a rapid liberation of the shot after tracing a long flight.

We will describe below, simply as an example, various forms of embodying this projectile and its braking device, making reference to the annexed drawing in which

Fig. 1 shows a side view of one form of projectile;

Fig. 2 is a vertical diametrical section of the hollow projectile or case proper showing the use of a charge of lead dust for slow and late evacuation;

Fig. 3 is a section similar to Fig. 2 of a killing projectile loaded with sporting shot;

Fig. 4 shows in section the projectile fixed to a retarding device in unfolded position,

said device consisting of a tassel of textile material kept under the projectile by means of a connector and a relatively elastic wad which forces it to open;

5 Fig. 5 shows the manner of loading up the tassel to introduce it into the tube of the cartridge case; and

Fig. 6 is a section of a loaded cartridge after closing;

10 Fig. 7 shows the arrangement of a thin layer of fibrous or flexible material held under the bottom of the projectile by a spring washer;

Fig. 8 is a plan view of Fig. 7;

15 Fig. 9 shows the manner in which the projectile thus furnished fits into the cartridge case, and

20 Fig. 10 is a side view of a variation in construction in which the retarding and tracing device is constituted by a small parachute fixed to the bottom of the projectile by cords.

25 As will be seen from Figs. 1, 2 and 3, the projectile proper is constituted by a cylindrical case 1 having on its periphery several slight projections or longitudinal or other ribs 2, having for their object to effect the guiding of the projectile in the smooth barrel, and to facilitate the passage through the choke so as not to cause too great a resistance there, and a thicker bottom or base, preferably reinforced by a rigid washer 3 and provided at the bottom with a small perforation 6 in which the retarding member may be fixed directly or indirectly. This hollow case has 30 a hemispherical or pointed head 4, the extremity of which has a central opening 5. This case is filled with a charge of shot 7, the weight and size of the grains of which are calculated according to the use for which the projectile is intended.

10 Figs. 1 and 2 show a projectile which is intended for tracing only, and it will be noted that its head 4 is more spherical, the walls of the head are thicker, and the aperture 5 of a smaller diameter and the case is filled with much finer shot (lead dust), than the lethal projectile shown in Fig. 3.

15 The retarding device consists essentially of a tassel or tuft, flexible and elastic, or jointed, formed for example of wool, silk, linen or woven material, rubber, or even wires or elastic or jointed metal blades, so as to expand compulsorily and be kept expanded after leaving the barrel, notwithstanding the action 20 of the wind or the pressure of air which should tend to close it, as in Figs. 4, 5 and 6. If the material of this retarding device is not sufficiently resilient in itself, it may be kept unfolded by a mechanical device such as that shown in Figs. 7 and 8, or it may be formed by a kind of parachute as in Fig. 10.

25 The tuft according to Fig. 4, is made of threads of silk or of twisted wool 8, in which may be incorporated a number of steel wires and rests on an elastic felt pad 9 preferably

having a diameter slightly larger than the internal diameter of the cartridge case 11, Fig. 6. This pad 9 and the tuft 8 are traversed by a connecting piece 10, for example, of twine which connects them together, passing through the hole 6 of the washer 3. To introduce this projectile in the cartridge case, the threads are collected towards the projectile as seen in Fig. 5, and the pad 9, which contracts sufficiently, is pushed into the case; 30 by the pressure on the projectile during closing, the wad 9 and the tuft 8 are more or less compressed but expand on passing out of the barrel when the shot is fired. In flight, the air has even a tendency to throw back 35 too many of the threads of the tuft which would destroy its visibility and its braking action; the purpose of the flexible pad 9 is therefore, to prevent them from closing together, and it is for the same purpose that it 40 is useful to mix a few steel wires with the wool threads.

45 In the variation according to Figs. 7, 8, and 9, the tuft 8 is presumed to be made of hair or bristle and the pad 9 which supports it 40 is composed of two layers of felt and cloth between which is held in a suitable manner a star or cross 11 cut from a thin steel spring plate. After the introduction into the cartridge case, as shown in Fig. 8, the arms of 50 this cross 11 are slightly curved towards the projectile and the tuft 8 is located in the hollow thus formed. On forming, these arms support the wad 9 and prevent the tuft 55 from yielding too much to the action of the air.

Finally, in Fig. 10, the tuft is replaced by a hollowed member 12 of woven material, rubber, or other material fixed to the projectile by a number of cords 10, and opening 105 as a parachute under the action of the wind.

60 It is evident that numerous variations may be made without departing from the invention, and that any suitable material may be used for making the parts which are indicated under the general term of "tuft" and "pad", in order not to lengthen the description by enumerations. For example, a washer of woven material or of rubber might be used of a diameter sufficient to form a bell 110 or skirt, and a wad consisting of a block of rubber or a spring device.

65 Furthermore, the elements used may be fire-proof, painted, dyed, or rendered phosphorescent, luminous, or brilliant to ensure 115 the visibility of the retarding and marking device under all atmospheric conditions.

70 Finally it should be noted that the invention consists in a visible projectile loaded with shot for regulating and increasing the 120 range, particularly for sporting guns, characterized by a hollow envelope retarded by an expanding device, this projectile and this 125 braking device being calculated in such a manner that the charge of shot only leaves it 130

at a definite distance, thus permitting the manufacture as desired of experimental projectiles or tracing projectiles, or killing projectiles ensuring a greater range and a better grouping of the shot.

5. I claim:

1. In a projectile for sporting guns, the combination with a non-rigid case containing a charge of shot and having a hemispherical forward end and a restricted aperture at said forward end, of an expandible retarding device associated with the rear of said case.

10. 2. In a projectile for sporting guns, the combination with a non-rigid case and a charge of lead shot or dust contained there, said case having a restricted exit aperture for said shot at the forward end, of a forcibly expanded retarding device having a 20 diameter larger than the base of the case and operatively connected thereto.

15. 3. In a projectile as set forth in claim 1 where the degree of conicity of the case head and the relative proportions of the retarding device are proportioned whereby the projectile may be employed as a tracer projectile or 25 as a lethal projectile.

20. 4. A projectile as set forth in claim 1 in which the retarding device consists of a tuft of textile material secured to a pad of elastic felt having a relative diameter larger than the bottom of the case and operatively connected to the rear of said case.

25. 5. A projectile as set forth in claim 2 wherein a resilient material is incorporated with the tuft of textile material whereby to prevent the tuft from closing together upon the passage of the projectile through the air during its flight.

30. 6. A projectile as set forth in claim 1 in which the retarding device comprises a parachute-like element opening under the pressure of air or wind when said case is fired from a gun.

35. 7. A projectile as set forth in claim 1 in which the retarding device is of a larger size than that of the base of the case so as to be visible during the flight of the case in order that the projectile may be used for tracing 40 purposes.

45. 8. In a projectile suitable for tracing purposes as set forth, a non-rigid case with a round head having a small central exit aperture, said case being loaded with fine shot whereby said shot leaves the case through 55 said aperture after the projectile has traversed a comparatively great distance.

60. 9. In a projectile as set forth having a shot case and a non-rigid case therein, a retarding device comprising a number of threads of textile material having wires incorporated therein and a spring washer sandwiched between two layers of felt within the shot case 65 and cooperatively connected to said device

whereby the flight of said projectile can be followed after firing from a gun.

10. In a projectile having a cartridge case and containing layers of explosive material therein, a case within said cartridge containing shot therein and having a rounded tapering forward end with an exit opening at the center of said end and a retarding device of slightly larger diameter than the bottom portion of said case and attached to the opposite end of said case, said retarding device being adapted to open and trail the case in its flight from the cartridge whereby its course of flight can be traced.
